UNITED STATES PATENT OFFICE

WILLIAM F. GROENE, OF CINCINNATI, OHIO, ASSIGNOR TO THE R. K. LE BLOND MACHINE TOOL COMPANY, OF CINCINNATI, OHIO, A CORPORATION OF DELAWARE

MOTOR TRAVERSE FOR LATHES

Application filed August 28, 1928. Serial No. 302,540.

My invention relates to the provision of a motor driven traversing device for the cross-slide and slide or carrier of a lathe in which the motor is carried on the slide or the apron thereof.

It has been the practice in recent years to provide lathes with rapid drives as well as working speed drives, so as to permit the operator to bring his tools up to working position without waste of time and retract them speedily after the work is completed. The necessity of providing two radically different drives for lathe carriages and slides has led to considerable expense and undue complication of the feeding mechanisms and transmissions and their cooperating structures.

It is my object to mount an electric or other type of motor on the lathe carriage, and provide a transmission therefrom for traversing the carriage apron. It is a further object to combine with the motor switch a gearshifting mechanism for changing from forward to reverse the power applied by the feed rod. Still another object is to avoid the use of transmission clutches and to apply the power of the motor to the slide and cross-slide through a roll-over clutch through which the power from the feed rod is also supplied.

Another object is to provide for a change gear device whereby the motor traverse can be applied to the main carriage feed or the cross-slide feed alternatively or simultaneously.

Generally it is my object to permit the operator, having first arranged the gearing for forward or reverse movement, to start a rapid movement and stop the same by merely depressing an electric switch (or a control valve which is its analogue), whereupon if the work feed is in operation it will start to operate as soon as the motor slows down. I am thus able to omit entirely the provision of high and low speed pulleys, extra gearing, extra transmission rods, shafts, controls and clutches, by employing a very minor addition to the gearing and shafting in the carriage apron.

An illustrative embodiment of my invention is shown in the accompanying drawings,

and will be fully described, whereupon claims will be appended setting forth the novelty of the invention.

In the drawings:

Figure 1 is a front elevation of the carriage of a lathe.

Figure 2 is a section on the general lines 2-2 of Figures 3 and 4.

Figure 3 is a section on the lines 3-3 of Figures 1 and 2.

Figure 4 is an end view at the motor end of the apron with the cover plate removed.

Figure 5 is a section on the lines 5-5 of Figures 1, 2, and 3.

Figure 6 is a longitudinal sectional detail of the roll-over clutch and concentric shaft arrangement whereby the motor drive is applied to the lathe, on a larger scale than the other views.

As stated, the basis of design whereby I apply the power from a self contained motor to carriage and cross-slide gears, is the maintenance of normal design of as much simplicity as possible except for the provision of a quill shaft or hollow shaft slipped over the feed rod, to which quill shaft the feed rod is coupled in the friction position of a roll-over clutch, and to which quill shaft the motor drive is applied in the free rolling position of said clutch.

I have thus indicated the usual lathe bed 1 with its feed rack 2 on the under side thereof. The feed rod or splined shaft 3 of usual lathe structure passes through the carriage 4, which is guided and held on the V's of the bed. The dovetail guideways 5 on the carriage guide and retain the cross-slide (not shown) and have located in the space between them the feed screw 6, to which power is applied by the pinion 7 fast thereon. The carriage has the usual apron 8, which carries the transmission gearing and parts.

The hand feed of the carriage is supplied in the usual way by a hand wheel 9 located on a shaft 9a which is journaled in the apron. The pinion 10 on the shaft 9a meshes with an intermediate gear 10a on a common shaft with the pinion 10b that engages the rack 2 on the bed.

Power is applied to the cross-slide feed

screw pinion 7 by a mechanism which can be shifted into and out of mesh therewith. To this end a shaft 11 is mounted in bearings in the apron so as to be slidable therein, and 5 carries a gear 12 which, in the outer position of the shaft, meshes with the pinion 7. This shaft also carries a gear 13 which, in the inner position of the shaft, meshes with the gear 10a of the main carriage feed.

10 Power is applied to the gear 12 in both of its positions by a wide face pinion 15 on the stub shaft 14, which shaft also has a beveled gear 16 at its inner end.

15 Mounted over and revoluble with relation to the feed rod or feed shaft 3 is the hollow shaft or quill shaft 17. A key 17a on the exterior of the quill shaft engages in a key way 18a of a gear sleeve 18 which is slidable but non-rotatable on the quill shaft. The 20 gear sleeve has the bevel gear portions 19 and 20 integral therewith, and is moved to and fro by engagement of a shifter pin with its grooved collar 21.

25 To this end a shaft 22 is mounted in the apron and equipped with a depending arm 23, on the end of which arm is a stud 23a that engages the collar. The shaft 22 is rocked by a handle 24 external of the apron, and the handle has a notched sector 25 with 30 teeth 26 which pass over a spring detent pin in the apron. This pin or plunger 27 engages in said teeth and serves to locate and hold the shifter handle in its several positions until dislodged by the force exerted by the 35 operator.

The operator can, by shifting the handle lastly described, move either the gear 19 or the gear 20 into mesh with the gear 16, and thus apply power in a controlled direction 40 to the gear 12. By shifting the gear 12 and its accompanying pinion he can thus apply power from the quill shaft either forward or reverse to the cross feed screw or the carriage feed pinion.

45 The quill shaft is alternatively driven by the following mechanism:—At the far end of the carriage is located a roll-over clutch or roller ratchet gear having the internal element 28 which carries a key 29 engaging the splined shaft 3 at any position of the carriage relative to said shaft. The pockets 30 in the internal element 28 contain the balls or rollers 34. A ring gear 31 constituting 50 the outer element of the roll-over clutch is held fast to the quill shaft by means of being bolted to a flanged collar 32 thereon. An annular plate 33 on the other face of the gear holds the rollers in their pockets, and the 55 internal element is held against endwise movement in the carriage by means of the outer element of the clutch.

The electric motor 35 mounted on the lower portion of the apron has a gear 36 on its rotor shaft which engages with the gear 31, forming

60 the external element of the roll-over clutch.

The splined shaft or feed rod 3 drives the internal element of this clutch which will drive the external element by causing the 70 rollers of the clutch to move to clamping position. The splined shaft will normally be driven at the desired working speed continuously during the operation of the machine.

75 The effect of starting up the motor will be to rotate the ring gear or external element of the clutch rapidly, which will result in the rollers in the clutch rolling away from the narrow end of their pockets, so as to permit the quill shaft to be driven rapidly irrespective of the movement of the splined shaft.

80 During the period when the motor switch is open and the splined shaft is furnishing the power, the rotor of the motor will be revolved, but in the absence of currents of electricity, will apply little, if any, load to the 85 operation of the feed.

I have not shown the motor switch except to indicate its position at 37, having a push button 37a. The switch will be of any standard construction in which the depression of the button will alternately open and close the switch, and in which the button is pushed outwardly at all times by a spring. In such switches the push button is equipped with a 90 pawl which operates on a ratchet, said ratchet serving to rotate a snap switch to alternate open and closed positions, although any 95 analogous construction may be used.

A rock shaft 38 mounted in the apron is 100 equipped at its upper end with a pair of crank fingers 39 serving as operating members, and is provided with a crank finger 40 at its lower end to engage the switch button.

105 The sliding pins 41 in the apron engage the pair of crank fingers 39, so that depression of either pin will result in moving the switch button, the spring on the switch button serving to keep the parts just described in a normal off position. A plunger 42 is 110 secured to a rocking finger 42a held on the handle 24 of the shifter mechanism in such a position that it is in position of engagement with one of the two pins 41 at the extremes of the shifter handle movement, and at the 115 neutral position of the handle does not engage either pin. Thus the motor switch cannot be operated unless the gearing for forward or reverse feed is in mesh.

120 The operation of the parts of the mechanism have been described, and a description in detail of the operation of the entire device will not be necessary. The operator will, at the outset of his operations, set the usual feed devices in motion. If the carriage is to be moved he may shift the shaft 11 by grasping its projecting end and pushing it inwardly. He will then set the shifter handle to select the desired direction and depress the lever 42a with his finger, where- 125 130

upon the motor will rapidly traverse the carriage to the desired point. He will then depress the lever again which will stop the motor and the carriage will feed slowly until the shaft 11 is pulled outwardly, or the 5 operator moves the shifter handle to neutral position.

Pulling the shaft 11 outwardly will couple the cross-slide feed screw to the drive, whereupon the operator may again select his 10 direction and depress the switch operating lever so as to traverse the cross-slide rapidly, thus bringing the tools up to the work.

When the tool or tools have been brought 15 to working position the operator depresses the lever 42a again, which results in the motor stopping and the regular splined shaft picking up the feeding operation of the cross-slide at whatever working speed has 20 been selected.

It will be evident that the particular gear arrangements may be varied by the use of equivalent structure, and that further refinements such as preventing the motor and 25 the hand wheel from revolving during rapid traverse could be supplied if necessary.

Essentially there is no addition to regular lathe practice in my structure as illustrated except in the quill shaft and roll-over 30 clutch and provision of means for coupling the cross feed to the carriage feed for attaining a rapid traverse of the carriage while the cross-slide is uncoupled.

Having thus described my invention, what 35 I claim as new and desire to secure by Letters Patent, is:—

1. In a lathe the combination with a carriage movable thereon and a cross-slide movable on the carriage, of a work feed shaft, a motor located on the carriage, and means 40 for selectively transmitting motion from the shaft and the motor to the cross-slide, said means including a direction changer, a switch for the motor, and means for operating the switch at selected positions only of the direction changer.

2. In a lathe the combination with a bed, a carriage movable thereon, and a cross-slide movable on the carriage, carriage feeding and cross-slide feeding elements mounted on the carriage, a transmission mechanism selectively applicable to said elements, a feed shaft, and a motor for rapid traverse, and means for selectively applying the shaft and the motor to said transmission mechanism, 50 said transmission mechanism including a direction changer, a switch for the motor, and means for operating the switch at selected positions only of the direction changer.

3. In a lathe the combination with a carriage movable thereon and a cross-slide movable on the carriage, of a work feed shaft, a motor located on the carriage, and means 55 for selectively transmitting motion from the shaft and the motor to the cross-slide, said

means including an element having a neutral position to break the transmission, a switch for the motor, and means for operating said switch at other than neutral position of said element.

4. In a lathe the combination with a carriage movable thereon and a cross-slide movable on the carriage, of a work feed shaft, a motor located on the carriage, and means for selectively transmitting motion from the shaft and the motor to the cross-slide, said means comprising a roll-over clutch, to one element of which power from the shaft is applied, and to the other element of which power from the motor is applied, and said transmission means also including an element having a neutral position to break the transmission, a switch for the motor, and means for operating said switch at other than neutral position of said element.

5. In a lathe, a bed and carriage, cross-slide feeding means on the carriage, an internal and external shaft, the latter driving the said feeding means, the internal shaft carried on the bed and the external shaft slidable on the internal shaft with the carriage, a motor on the carriage, and means for operatively connecting the motor to the external shaft and the internal shaft to the external shaft.

6. In a lathe, a bed and carriage, cross-slide feeding means on the carriage, an internal and external shaft, the latter driving the said feeding means, the internal shaft carried on the bed and the external shaft slidable on the internal shaft with the carriage, a motor on the carriage, and means for operatively connecting the motor to the external shaft and the internal shaft to the external shaft, said means formed as a roll-over clutch.

7. In a lathe, a bed and carriage, cross-slide feeding means on the carriage, an internal and external shaft, the latter driving the said feeding means, the internal shaft carried on the bed and the external shaft slidable on the internal shaft with the carriage, a motor on the carriage, and means for operatively connecting the motor to the external shaft and the internal shaft to the external shaft, said means formed as a roll-over clutch, means for selectively applying the external shaft to the cross-slide feeding means in forward or reverse, and a switch for the motor controlled by the last named means.
